W. M. Williams Design for Ladies' Hat
Patented Number 940,000
DES 520

Des. 520

Washburn Race of Seneca Falls, N.Y.

As prior to

H. C. Silsby, W. Race, & Birdsill Holly of same place.

Letters Patent No 520 Dated Nov. 9th 1852.

The schedule referred to in these Letters Patent and making part of the same

To all whom it may concern:

Be it known That I, Washburn Race, of Seneca Falls, in the County of Seneca, and State of New York, have invented a new ornamental design for plates and feet of a Parlor Stove; and I do hereby declare that the following is a full, clear and exact description of the same, reference being had to the accompanying drawings forming part of this specification, in which

Fig 1. is a plan of the base plate.

Fig 2. is a sectional profile of the same.

Fig 3. is a plan of the plate surmounting the body of

Fig 4. is a sectional profile of the same.

Fig 5. is the top or cap plate.

Fig 6. is a sectional profile of the same.

Fig 7. is a face view of one of the feet, and

Fig. 8. is a profile section of the same.

The base plate Figs 1 & 2, is in the form of an ellipse and surrounded by a moulding A, whose form is best shown in Fig 2, having upon it an ornamental device a, b. (see Fig 1.) repeated all round continuously, excepting on one side where it is varied at one point by a somewhat different device c, d. Within the moulding A, is a moulding B, whose form is best shown in Fig 2, and upon this moulding is a raised ornament of scroll work consisting of a continuous repetition of the device f, g. all round (see Fig 1.)

The plate shown in Figs 3 & 4, is also of elliptical form and surrounded by an open scroll work ornament formed of the continuous repetition of the device e, h. which except that the spaces between the ornament are open resembles the device a, b. on the base plate. At one point n, the ornament is slightly diversified (see Fig 3).

The top or cap plate B, of similar form in outline to the others, is surrounded by a moulding C, whose form is best shown in Fig 6, and upon the face of this moulding is a continuous repetition of the ornament f, g. See fig 5, similar to that f, g. on the base plate. Within the moulding C, a small portion of the plate is flat, then an ornament k, extends all round, and within k, there is an ornament l, one half only of which is shown as the other half is but repetition, and within l, a small ornament m, is continued all round, surrounding the whole.

The feet are ornamented with raised scroll work of the form and design shown in Fig 7, the general form being that of a Cyma recta.

What I claim as my invention and desire to secure by Letters Patent is

That I claim as my invention and desire to

The design and configuration of the several plates, and of the feet, and also of the ornaments a, b, c, d, e, h, f, g, and m, separately as herein shown and described.
